UNITED STATES PATENT OFFICE.

LOUIS W. DRAPER, OF CHICAGO, ILLINOIS.

BOX.

1,025,253.

Specification of Letters Patent.

Patented May 7, 1912.

Application filed July 5, 1910. Serial No. 570,216.

To all whom it may concern:

Be it known that I, LOUIS W. DRAPER, a citizen of the United States, residing at Chicago, in the county of Cook and State 5 of Illinois, have invented certain new and useful Improvements in Boxes, of which the following is a specification.

My invention relates to improvements in paper boxes and has for its object the production of a box which will be so constructed that access to the interior thereof may be readily effected without necessitating the removal of the cover thereof.

A further object of my invention is the provision of a box of the character mentioned which will be of strong and durable construction and efficient in operation.

Other objects will appear hereinafter.

With these objects in view my invention 20 consists in a box characterized as above mentioned and in certain details of construction and arrangement of parts all as will be hereinafter fully described and more particularly pointed out in the appended claim.

25 My invention will be more readily understood by reference to the accompanying drawing forming a part of this specification, and in which,

Figure 1 is a plan view of the blank from 30 which the body of a box embodying the preferred form of my invention may be formed, Fig. 2 is a plan view of the blank from which the cover for said body may be formed, Fig. 3 is a bottom plan view of the 35 cover in completed condition, Fig. 4 is a central vertical section of the preferred form of my box, one side thereof being shown extended to permit of access to the interior thereof, and Fig. 5 is a similar section of a 40 slightly modified form of my box.

Referring now to the drawing, 1 indicates the blank from which is formed the body of my box. Said blank is creased at 2 to form the central bottom portion 3, the front and 45 rear portions 4 and 4' respectively, and the side portions 5 and 5'. The ends of the walls 4 and 4' are extended as shown and creased at 6 to form flaps or ears 7-7 and 8-8 respectively.

50 The cover-forming blank 9 is creased at 10 to form a central top portion 11 and flange portions 12, the ends of two of the latter at opposite sides of the portion 11 being provided with flaps or ears 13 which 55 are adapted to be rigidly secured as by rivets 14 to the adjacent ends of the other

portions 12 to maintain said portions 12 in rigid relation with the body portion 11, as shown in Fig. 4. When in operative or folded condition the portions 4-4' and 5-5' of the body are held in position by means of the flange portions 12 of the cover, said flange snugly engaging over the upper ends of the former. However, said flange, it will be observed, serves only to hold said 60 walls of said body against outward movement. Inward movement of the walls 4 and 4' is prevented by the inner edges 15 of the flaps 7-7 and 8-8 which rest against the bottom of said body; inward movement 70 of the walls 5 and 5' being prevented by the extremities of the walls 4 and 4' against which the ends of said walls 5 and 5' abut.

The outer corner portions of the flaps 7-7 are cut away as at 16 in order to permit of the outward rocking of the wall 4 when the front edge of the cover is elevated sufficiently to release the same, as shown in dotted lines in Fig. 4. Said flaps, as seen, are so formed as to permit of the lowering 80 of the cover to initial or closing position when the wall 4 is in open condition, said flaps, as seen, affording clearance for the flange of the cover when the latter is lowered. Thus it will be seen that access may 85 be gained to the interior of the box without necessitating the removal of the cover. The end 4 may be also readily closed without previously raising the cover as the edges of the flaps 7 serve as cams to automatically 90 raise the cover as the end is pushed inwardly.

In the modified form the front flange portion of the cover or that positioned adjacent the wall 4 of the body of the box is 95 loose or free for outward swinging, the flaps 13 thereof not being secured to the contiguous ends of the adjacent flange portions. With this provision, in order to permit of outward swinging of the body wall 100 so that access to the interior of the box may be gained, it will be unnecessary to even elevate the front edge portion of the cover, as in the case above described, it requiring, in this form, only the outward swinging of the 105 front portion of the flange of the cover, as clearly shown in Fig. 5, to permit of such operation. When the box is in closed condition the flaps 13 of the front flange portion of the cover and the side flanges of the 110 front portion of the box are inserted into the box at each side to retain the parts in

position as shown. If such clamping of the flaps 13 is not sufficient to hold the wall 4 closed as mentioned, a locking device of suitable design may be employed to secure 5 the same in position.

A box of the construction as shown and described is particularly adapted for use in many instances, but more especially in places where it is desired or necessary to pile a 10 number of boxes containing goods one above the other, and where the goods contained therein are frequently removed therefrom and replaced therein. By the employment of boxes of my construction in such places a 15 great saving of time and labor would evidently result.

While I have shown what I deem to be the preferable forms of my box I do not wish to be limited thereto as there might be various changes made in the details of construction and arrangement of parts described without departing from the spirit 20 of the invention comprehended within the scope of the appended claim.

25 Having described my invention what I

claim as new and desire to secure by Letters Patent is:

A box comprising a body having a bottom, sides integral with said bottom, and front and rear portions integral with said 30 bottom and having side flaps loosely fitting within said sides, and a cover having depending flanges engaging the front, back and sides of said box to hold the same in box form, the outer corner portions of the 35 flaps on said front being cut away on curved lines to facilitate swinging the flaps into and out of said box, to permit the end to be in opened position while the cover is in place and to automatically raise the 40 cover as said front end is pushed inwardly, substantially as described.

In testimony whereof I have signed my name to this specification in the presence of two subscribing witnesses.

LOUIS W. DRAPER.
